UNITED STATES PATENT OFFICE.

ALFRED E. HOLMBERG, OF MAPLE LAKE, MINNESOTA.

GRAIN-BINDER DECK.

1,239,791.

Specification of Letters Patent. Patented Sept. 11, 1917.

Application filed November 6, 1915. Serial No. 59,921.

To all whom it may concern:

Be it known that I, ALFRED E. HOLMBERG, a citizen of the United States of America, residing at Maple Lake, in the county of 5 Wright and State of Minnesota, have invented certain new and useful Improvements in Grain-Binder Decks, of which the following is a specification.

The present invention relates to harvesters and pertains more particularly to that 10 type of harvesters known as binders.

The present invention has for one of its 15 objects to produce a binder that will not wedge the grain against the top and thereby become clogged.

Another object is to provide a binder that will cut regardless of the condition of the ground, whether it be dry, hard, soft or wet.

Still another object is to provide a binder 20 that will cut through any kind of grain, such as grain full of grass and weeds, and if the grain should be wet, without clogging the binding mechanism.

With these and other objects in view, the 25 invention consists in the construction, combination and arrangement of parts as will be hereinafter described and claimed.

Reference is to be had to the accompanying drawings forming part of this specification, 30 in which similar reference characters indicate corresponding parts throughout the various views, and in which—

Figure 1 is a sectional view on the line A—A of Fig. 3.

35 Fig. 2 is a top plan view.

Fig. 3 is a bottom plan view.

Fig. 4 is a perspective view of the movable deck section, and

Fig. 5 is a view of the lever bracket.

40 Referring more particularly to the drawings, 1 indicates the binder deck, 2 the needle, the arm of which is an arc instead of being somewhat straightened as is commonly in use today, and 3 the curved arm thereof.

45 Pivotedly secured to the deck 1, as at 5 and 6, and operating in an opening 7 is a platform 8, having extending longitudinally thereof a slot 9 through which the needle operates.

50 Underneath the binder deck is a plurality of bearings 10 with shafts 11, 12 and 13 rotating therein. The shafts 11 and 12 are connected to the platform 8 by offsets 14 of the shafts which engage in recesses 15 formed in the downturned edges of the plat-

form and are maintained therein by plates 16 having recesses therein complementing the recesses in the platform, while shaft 13 controls the needle 2, deriving its power from a source not shown.

60 A rod 17 is loosely connected to one of the offsets 14 and to a pin 18 secured to a lug 19 on the needle 2, causing the platform 8 and needle to work in unison so that the deck will press the gavel against the top.

65 One of the shafts 12 extends slightly beyond the edge of the deck and is in fixed engagement with a bar 20, which has at its free end a pin 21 extending at right angles thereto. A lever 22 has one end curved, 70 as at 23, to provide a gripping means, and the opposite end slotted, as at 24, to slidably receive the pin 21. A portion of the under side of the lever 22 is serrated to form teeth 25, one edge of which is abrupt and 75 the other inclined, affording means of adjusting the platform with respect to the deck.

80 A bracket 26, secured in any well known manner to the binder deck, has adjacent its top an opening 27, in which is mounted a spring 28 having one end bearing against the lever 22 to fixedly engage the teeth thereon with the bracket. The other end of the spring is held in position in the opening by 85 a bolt 29.

85 When cutting grain in dry weather or under ordinary conditions the platform is fixed in its uppermost position, but if the ground is soft or the grain damp or full of 90 foreign growth, the deck is lowered to the proper requirements by releasing the serrations in the lever from the bracket and making the proper adjustment at this point. By lowering the platform a greater amount of space is provided between that portion of the deck which supports the bundle and the binder top, thus eliminating the fault of having the grain jammed or clogged between the deck and top hindering the proper 95 operation of the binding mechanism.

100 The peculiar curve of the needle arm pushes the grain forward without wedging it against the top, thereby causing much less friction and less power to push it through. The curved arm and the movable section co-operate in functions and make work easier, and, if the friction becomes too severe, the section is put in motion making more space 105 between it and the top.

110

Various changes in form, proportion and the minor details of construction may be resorted to without departing from the principle or sacrificing any of the advantages of this invention as claimed.

What I claim is:—

1. A binder having a deck with an adjustable and movable section, a shaft for adjusting the position of the section rotatably connected to the deck, means connected to the shaft for moving the same, a needle and needle shaft, a second shaft secured to the deck and section, and a rod connecting the needle and second shaft for contemporaneously moving the adjustable section with the needle.
- 10 2. A binder having a deck with a movable and adjustable section, shafts rotatably connected to the deck and said section, a needle having a lug thereon, and a bar connected to said lug and one of the shafts.
- 15 3. A binder having a deck with a movable and adjustable section, shafts rotatably connected to the deck and said section, a needle, and a bar connected to one of the shafts and

the needle for moving the section and needle in unison.

4. A binder having a deck with an adjustable and movable section, shafts rotatably connected to the deck and section, a needle, a bar connected to the needle and one of the shafts for moving the needle and section in unison, and a lever connected to the other shaft for adjusting the said deck.

5. A binder having a deck with a movable section, said section being provided with a central longitudinal needle opening and downturned edges having a plurality of recesses therein, crankshafts connecting the deck and section and received in the recesses, a needle operating in the opening and connected to one of the crankshafts, and means for operating the needle.

In testimony whereof I affix my signature in the presence of two witnesses.

ALFRED E. HOLMBERG.
